UNITED STATES PATENT OFFICE.

LEON ADDISON WATTS, OF LANCASTER, SOUTH CAROLINA, ASSIGNOR TO ALLIS-CHALMERS MANUFACTURING COMPANY, OF MILWAUKEE, WISCONSIN, A CORPORATION OF DELAWARE.

GUIDE VANE.

Application filed January 18, 1923. Serial No. 613,355.

To all whom it may concern:

Be it known that LEON A. WATTS, a citizen of the United States, residing at Lancaster, in the county of Lancaster and State 5 of South Carolina, has invented a certain new and useful Guide Vane, of which the following is a specification.

This invention relates in general to improvements in turbine structures, and relates 10 more specifically to improvements in the construction of guide vanes for hydraulic turbines and the like.

An object of the invention is to provide an improved guide vane for hydraulic turbines 15 and the like, which is simple in construction and efficient in operation.

It has heretofore been proposed to construct guide vanes for controlling the direction and quantity of water delivered to a 20 hydraulic turbine, of sheet metal. Such prior guide vanes ordinarily consist of a sheet metal body and one or more pivots associated with the sheet metal body in any convenient manner, the pivots serving 25 to permit adjustment of the guide vanes in order to regulate the flow of water past the vanes. Under certain conditions of operation it has been found necessary to reenforce the sheet metal bodies of such guide vanes 30 by providing internal braces coacting with the opposite sheet metal walls of the vanes.

The present invention contemplates provision of simple and relatively inexpensive means for adding rigidity to sheet metal 35 guide vane structures. The invention consists of placing cement, concrete or similar material in the interior of a sheet metal guide vane in order to resist external pressures upon such vanes. The concrete or 40 other material thus inserted within the sheet metal body of the vane may either completely or only partially fill the vane and may be reenforced if desired.

A clear conception of an embodiment of 45 the present invention may be had by referring to the drawing accompanying and forming a part of this specification in which like reference characters designate the same or similar parts in the several views.

Fig. 1 is a part sectional top view of a 50 concrete reenforced sheet metal guide vane.

Fig. 2 is a part sectional side elevation of a concrete reenforced sheet metal guide vane.

The guide vane illustrated in the drawing 55 comprises a pair of integrally united sheet

metal side plates 2, 3 preferably formed of a single sheet of metal bent to the desired shape with the aid of dies and united at the discharge edge 9 of the vane by fusion of metal as by welding. The sheet metal body 60 is provided with upper and lower supporting blocks 6, 7 respectively, which are rigidly attached to the side plates 2, 3 in any suitable manner as by spot welds 13. The blocks 6, 7 are provided with integral upper 65 and lower pivots 4, 5 respectively, having central openings communicating with aligned openings in the blocks 6, 7 which are connected by means of a relatively small pipe 8 in order to permit the passage of lubricating fluid from one of the pivot stems 4, 5 to the other. In relatively large guide vanes the side plates 2, 3 may be properly spaced and braced by means of a plurality 70 of struts 12 as indicated. The interior of 75 the sheet metal body of the guide vane is preferably filled with concrete 10, cement, or other non-metallic filler having reenforcing wires 11 embedded therein, although the reenforcement is not a necessary element of 80 the structure. The concrete 10 may be readily admitted to the interior of the guide vane through the open ends thereof and may either completely or only partially fill 85 the vanes.

It will be noted that with a guide vane thus constructed the side plates 2, 3 are rigidly held in proper spaced relation against external pressure. The sheet metal forming the side plates 2, 3 may be readily bent to 90 the proper shape with the aid of dies. The blocks 6, 7 and the struts 12 are firmly embedded within the concrete 10 and the reinforcing wires 11 prevent the concrete 10 from breaking and falling out of the 95 guide vanes. The entire structure is relatively inexpensive and enables the use of material having relatively high wear resisting qualities for the surfaces which are exposed to direct contact with the 100 water. The concrete 10 besides effectively reenforcing the side plates 2, 3 adds desirable weight to the guide vane thereby aiding in efficient adjustment of the vanes. It will be obvious that while the pivot stems 4, 5 105 have been illustrated as being separated endwise and rigidly attached to the blocks 6, 7 respectively other forms of pivoting of the vane may be readily employed.

It should be understood that it is not de- 410

sired to limit the invention to the exact details of construction and of operation herein shown and described, for various modifications within the scope of the claims may 5 occur to persons skilled in the art.

It is claimed and desired to secure by Letters Patent:

1. A guide vane for turbines comprising, a sheet metal shell, and concrete reenforcement within said shell.
2. A guide vane for turbines comprising, sheet metal side plates, and non-metallic reenforcements between said side plates.
3. A guide vane for turbines comprising, 15 a single sheet metal wall formed to produce a hollow center, and a filling of non-metallic substances located in said center.
4. In a guide vane, a sheet metal outer wall, pivot blocks secured to said wall, 20 pivots associated with said blocks, and a filling of concrete within said guide vane and surrounding said blocks.
5. In a guide vane, a concrete core, sheet metal surrounding said core, and a plurality 25 of struts embedded in said core and connecting opposite portions of said sheet metal.
6. In a guide vane, a concrete core, sheet metal surrounding said core, blocks embedded in said core and attached to said

sheet metal, and pivots associated with said 30 blocks.

7. In a guide vane, a concrete core, a single sheet of metal surrounding said core, and pivots associated with said core and with said sheet.

8. In a guide vane, a concrete core, a single sheet of metal surrounding said core, 35 blocks embedded in said core and attached to said sheet, and pivots associated with said blocks.

9. In a guide vane, a reinforced concrete core, a single sheet of metal embracing said core, struts embedded in said core and connecting opposite portions of said sheet, and pivot blocks embedded in said core and attached to said sheet.

10. A turbine vane comprising, a sheet metal shell, and a concrete reenforcement within said shell.

11. A turbine vane comprising, a relatively thin metallic shell, and a concrete reenforcement within said shell.

12. A turbine vane comprising, a relatively thin metallic shell, and a non-metallic reenforcement within said shell.

In testimony whereof, the signature of the inventor is affixed hereto.

LEON ADDISON WATTS.
